CARTON FOR CIGARETTE PACKS

William E. Gagnon, Whitman, Mass.

Application October 5, 1954, Serial No. 32,547

Term of patent 14 years

(Cl. D58—13)

Figures 1 and 2 are perspective views of a carton for cigarette packs in open and closed conditions, respectively, showing my new design.

Figures 4 and 5 are front and end elevational views, respectively, of the same.

I claim:

The ornamental design for a carton for cigarette packs, as shown.
